UNITED STATES PATENT OFFICE.

WESTON M. FULTON, OF KNOXVILLE, TENNESSEE.

COLLAPSIBLE VESSEL FOR ATMOSPHERIC MOTORS.

SPECIFICATION forming part of Letters Patent No. 729,926, dated June 2, 1903.

Application filed November 21, 1901. Serial No. 83,178. (No model.)

To all whom it may concern:

Be it known that I, WESTON M. FULTON, a resident of Knoxville, Tennessee, have invented a new and useful Improvement in Collapsible Vessels for Atmospheric Motors, which invention is fully set forth in the following specification.

My invention relates to atmospheric motors, and more particularly to collapsible vessels which respond to variations in atmospheric temperature or pressure or to variations of both temperature and pressure, the movement of the collapsible vessel due to these causes being utilized to impart movement to a motor.

Heretofore many efforts have been made to construct a collapsible vessel which will offer but slight resistance to any force or forces tending to collapse or expand it. In order to accomplish this end, vessels have been made of a series of disk-shaped metal shells or of leather, oiled silk, or other very pliable material. The aneroid barometer, bellows, and Japanese lantern are illustrations. In order that the collapsible vessel should attain its highest ideal efficiency as a means of transmitting the power due to atmospheric changes, it is essential that the changes in volume due to the expansion and contraction of the vessel should be utilized so as to impart the greatest extent of motion to that portion of the wall of the vessel which is connected to the motor or thing to be moved. The collapsible vessels heretofore constructed fail to attain these ideal conditions, because the expansion or contraction of the vessel due to atmospheric variations does not take place along the line of one dimension only, but takes place along various diversified lines,

owing to the yielding of the delicate walls of the vessel. The result is that the movement in any one direction is much smaller than would be the case if the entire change in the volume of the vessel were directed along the line of one dimension. Moreover, collapsible vessels as heretofore constructed are open to the further objection that they respond too readily to slight atmospheric changes, and thus reach the limit of their range in volume before the limits in variations of atmospheric conditions are reached. Thus suppose the vessel to have collapsed to its minimum limit

at temperature t and pressure p and that the pressure remains constant while the temperature rises to $(t+x)$ degrees. Now if the load be light and the vessel very flexible the latter will expand to its greatest limit. If now the temperature continues to rise and remains for some time above $(t+x)$ degrees, the motor to which the vessel may be attached will remain idle during the entire time that the temperature thus remains above $(t+x)$ degrees, since the vessel has reached the limit of its expansion. The ideal condition is that the vessel shall so respond to atmospheric changes that it will reach its limit of expansion or contraction just when atmospheric conditions have reached the limits within which they usually fluctuate.

A still further objection to those collapsible vessels which, like the Japanese lantern, present sharp angles in the folds of the material of which they are constructed lies in the fact that such sharp angles result in lines of wear and ultimate cracks, which destroy the usefulness of the vessel.

One of the objects of the present invention is to construct a collapsible vessel of the character referred to whose changes in volume due to atmospheric variations shall take place along the line of one of the dimensions of the vessel.

A further object is to provide a collapsible vessel whose limits of expansion and contraction shall correspond as nearly as possible to the limits within which atmospheric conditions of temperature and pressure fluctuate; and, finally, the object of the invention is to provide a collapsible vessel which shall be free from sharp angles or folds resulting in premature wear and cracks.

With these objects in view the invention consists in a vessel containing an expansive fluid and having oppositely-disposed comparatively rigid walls connected by flexible walls, which latter walls yield only in a direction to permit the vessel to expand or contract along the dimension between said rigid walls. Preferably the vessel is circular in cross-section; but it may have any other desired shape, and the rigid walls form the end of the vessel, which are connected by the flexible walls. The flexible walls are preferably composed of thin sheet steel or brass having

shallow annular corrugations, which while permitting the vessel to expand or contract in volume in a longitudinal direction are stiff enough to prevent any yielding of the walls, so as to allow any increase or decrease of volume in any other direction. In some instances the upper and lower surfaces of these annular corrugations are also provided with minute corrugations, so as to stiffen said surfaces and prevent them from yielding except in the desired direction. It is to be understood, however, that these last-mentioned corrugations may be omitted, if desired.

The invention further consists of a collapsible vessel whose changes in volume take place along the line of one of its dimensions, combined with a spring or springs whose tension acts along the same line and tends to resist contraction and aid expansion or aid contraction and resist expansion of the vessel. The spring or springs may be of such dimensions as to resist contraction or aid expansion, or vice versa, throughout the entire range of said movements or only through a portion thereof, as may be deemed most expedient, and the vessel itself may be the corrugated form of collapsible vessel herein described, or any other preferred form may be employed in connection with the spring or springs above mentioned; and, finally, the invention consists in a collapsible vessel with yielding corrugated walls, the corrugations being struck on curves and free from sharp angles.

In addition to the above the invention consists in certain details of construction which will be hereinafter described and then pointed out in the claims.

The inventive idea may receive various mechanical expressions, and the accompanying drawings are therefore to be understood as illustrative only.

In said drawings, Figure 1 is a transverse vertical section of one form of collapsible vessel embodying my invention. Fig. 2 is a horizontal section thereof on the line 2-2, and Fig. 3 is a transverse vertical section of a modification.

Referring to the drawings, 1 is a collapsible vessel having rigid end walls or plates 3 and 4 and flexible side walls 5, the side walls being composed of any suitable material, as sheet brass or steel, and provided with corrugations 6, which are of such dimensions in proportion of the thickness of the walls that the corrugations will be stiff enough to resist any tendency of the external atmospheric pressure to buckle them inward or of the internal pressure to buckle them outward, while the flexibility of the wall as a whole is such as to permit the vessel to expand or contract in the direction of its length. In order to stiffen the corrugations 6 in a manner to prevent the buckling above referred to, the surfaces of these corrugations may themselves receive minute corrugations 7, though these may be omitted, if desired.

Centrally secured to one of the end walls,

as 4, is a spring 8, provided with a cap-piece or abutment 9, secured thereto, to which is attached arms 10, extending along a portion 70 of the length of the spring 8 and terminating in shoulders 11. The cap-piece 9, arms 10, and shoulders 11 may, if preferred, be in the form of a cylinder inclosing a portion of the spring and having at its open end an outwardly-projecting flange. Centrally secured to the opposite end 3 of the vessel is a part 12, preferably in the form of a cylinder, embracing the abutment 9 and having inwardly-projecting shoulders 13. In operation the vessel 1 collapses without meeting any resistance from the spring 8 until the end wall 3 contacts with the abutment 9, after which time any contraction of the vessel which takes place will be against the tension of the spring 8, and, vice versa, the expansion of the vessel will be aided by the resiliency of the spring 8 so long as the abutment 9 engages the end wall 3 of the vessel, after which the spring will have no effect. It will thus be seen that after the vessel is expanded to a predetermined point—that is, to the point where the abutment 9 is withdrawn from contact with end wall 3—the spring 8 is no longer under compression or expansion, and thereafter it is functionless till abutment 9 contacts with wall 3 or the bottom of cylinder 12. When it is desired, spring tension may be provided which offers continuous resistance to contraction and continuously aids expansion of the vessel 1, or vice versa. One mode of supplying such spring tension is shown in the symmetrically-disposed springs 14, here shown as three in number and extending from end wall 3 to end wall 4 of the vessel and engaging said walls at the apices of an equilateral triangle whose center is the center of the vessel, so that the spring-pressure is evenly distributed over the two end walls 3 and 4. In case it is desired the spring tension acting continuously on both end walls of the vessel may be employed without the interrupted tension of spring 8, and in such case a single centrally-disposed spring 15, Fig. 3, may be used. In this figure a different form of collapsible vessel is shown. This vessel consists of two cylinders 16 17, one disposed within the other and having a common base 18, the space between the cylinders being filled with some gas-sealing material, as mercury, 19. A third cylinder 20, open at one end, of greater diameter than cylinder 16 and less diameter than cylinder 17, is inverted with its open end immersed in the mercury 19, thereby forming a gas-tight vessel capable of expansion and contraction in a longitudinal direction. As shown, the spring 15 is centrally disposed in the vessel and contacts with the opposite end walls thereof. While I have herein shown the various springs as located within the collapsible vessel, it is to be understood that the springs may be located without the vessel, the only essential being that the spring tension be so applied as to resist

contraction or aid expansion, or vice versa, as hereinbefore indicated.

Referring to Fig. 1 and assuming that the vessel contains any suitable expansible fluid, 5 as a gas or gases or a gas and vapor, the tension of which fluid under normal atmospheric conditions would just equal atmospheric pressure, then evidently there would be no strain on the springs 14 in either direction. 10 Now if the atmospheric conditions should so change as to cause the fluid within the vessel to expand, the springs 14, being secured to the walls 3 and 4, would resist the expansion of the vessel, and when the atmospheric conditions changed, so as to cause the contained fluid to contract, the springs 14 would aid contraction of the vessel till contraction had reached a certain point where the springs 14 are neither under tension of extension or 20 compression, and below that point these springs would resist contraction and aid expansion, the function of the springs 14 in any particular case depending upon whether the expansion fluid within the vessel always 25 remains above atmospheric pressure or always remains below atmospheric pressure or is sometimes above and sometimes below atmospheric pressure. The true spirit of this 30 part of the invention is that the spring or springs shall so control the vessel as to prevent it from collapsing to its minimum limit or expanding to its maximum limit before atmospheric conditions have reached their extreme limits and, further, to insure that 35 the vessel shall give the greatest fluctuations in volume in response to those atmospheric changes which are of the most frequent occurrence and least fluctuations in response to those atmospheric changes of less frequent 40 occurrence the exact action of the spring or springs depending to a large extent upon the character of the expansive fluid used in the vessel.

What is claimed is—

45 1. A hermetically-sealed collapsible vessel, having oppositely-disposed rigid walls connected by a flexible wall, which is composed of substantially parallel portions united by portions struck on a curve, whereby a flexi-

50 ble corrugated wall is formed, in contradistinction to a flexible angular wall made up of perforated disks united at their exterior and interior peripheries.

55 2. A hermetically-sealed collapsible vessel, having oppositely-disposed rigid walls connected by a flexible wall, which is composed of corrugated portions approximately normal to the axis of the vessel and connected by approximately vertical curved portions.

60 3. A hermetically-sealed collapsible vessel having oppositely-disposed walls which approach and recede from each other when the vessel contracts and expands, a spring normally abutting one of said walls, and abutting the other wall when the vessel is contracted but not when said vessel is expanded.

65 4. A hermetically-sealed collapsible vessel

having oppositely-disposed walls which approach and recede from each other when the vessel contracts and expands, a spring normally abutting one of said walls, an abutment on the other end of said spring to which abutment outwardly-extending shoulders are secured, and corresponding shoulders supported on the opposite wall in position to 75 abut said shoulders when the vessel contracts.

5. A hermetically-sealed collapsible vessel having oppositely-disposed walls approaching toward and receding from each other 80 when the vessel contracts and expands, a spring abutting one of said walls, and a cylinder supported on the opposite wall and surrounding a portion of said spring.

6. A hermetically-sealed collapsible vessel 85 having oppositely-disposed walls approaching toward and receding from each other when the vessel contracts and expands, a centrally-disposed spring abutting one of said walls and having outwardly-projecting shoulders mounted thereon, a centrally-disposed cylinder secured to the opposite wall and having shoulders positioned to abut said outwardly-projecting shoulders upon the contraction of the vessel, and a plurality of 90 symmetrically-arranged springs in normal contact with both of said oppositely-disposed walls. 95

7. A hermetically-sealed vessel, combined 100 with an expansible and contractile spring, having its ends secured to the walls of the vessel, one end being secured by a lost-motion connection and of such length that when the vessel is expanded to a predetermined point the spring is neither compressed nor 105 expanded.

8. A hermetically-sealed collapsible vessel, 110 containing an expansive fluid, whose tension varies with changes in atmospheric conditions, combined with an expansible and contractile spring, having its ends secured to the walls of the vessel, one end being secured by a lost-motion connection and of such length that when the vessel is expanded to a predetermined point the spring is neither compressed nor 115 expanded.

9. A hermetically-sealed collapsible vessel, 120 having rigid end walls connected by a flexible wall having a series of regular, curved, non-angular corrugated corrugations.

10. A hermetically-sealed collapsible vessel, having oppositely-disposed rigid walls connected by a flexible wall composed of a series of parts approximately normal to the vessel's axis, and connected, alternate concave and convex portions.

In testimony whereof I have signed this specification in the presence of two subscribing witnesses.
